US00D479725S

(12) **United States Design Patent** (10) Patent No.: **US D479,725 S**
Lannoch (45) Date of Patent: **** Sep. 16, 2003**

(54) **ANGULAR GEAR**

(75) Inventor: **Hans-Jürgen Lannoch**,
Linkenheim-Hochstetten (DE)
(73) Assignee: **SEW-Eurodrive GmbH & Co.**,
Bruchsal (DE)
(**) Term: **14 Years**

(21) Appl. No.: **29/170,184**

(22) Filed: **Nov. 1, 2002**

(30) **Foreign Application Priority Data**

May 2, 2002 (DE) 402 03 875

(51) LOC (7) Cl. **15-09**

(52) U.S. Cl. **D15/148**
